(57) **CLAIM**

The ornamental design for a collapsible chick brooder, as shown and described.

DESCRIPTION

FIG. 1 is a front perspective view of a collapsible chick brooder showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken line portions in FIGS. 1-7, showing a front gate lock, a front gate handle, handles on the sides of the brooder body, fasteners, etc., are presented for illustrative purposes and form no part of the claimed design. The double dashed lines in FIGS. 1, 4-5, 7 depict fold lines and form part of the claimed design.
